UNITED STATES PATENT OFFICE.

FRANK L. RUMBLE, OF LOWELL, OHIO.

WHEEL-HARROW.

SPECIFICATION forming part of Letters Patent No. 293,520, dated February 12, 1884.

Application filed October 26, 1883. (No model.)

To all whom it may concern:

Be it known that I, FRANK L. RUMBLE, a citizen of the United States, residing at Lowell, in the county of Washington and State of Ohio, have invented certain new and useful Improvements in Harrows; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a perspective view. Fig. 2 is a vertical section taken just in front of the axle. Fig. 3 is a perspective view of the axle-guide. Fig. 4 is a front view of the stop-plates, and Fig. 5 shows a horizontal section through the same. Fig. 6 is a perspective view of the stop-plates.

This invention has relation to wheel-harrows; and it consists in the construction and novel arrangement of parts, as will be herein-
25 after fully described, and particularly pointed out in the claim appended.

Referring by letter to the accompanying drawings, *a* designates the harrow-frame, which is preferably three feet wide at the front, the side rails, *b b*, diverging to a width of six feet at the rear, the length of the frame being seven feet. The roller *c* of a tongue, *c'*, is pivoted between the side rails, *b b*, at the front end, and a curved rod, *d*, extending slightly forward, connects the front ends of the side rails, *b b*, and prevents the tongue *c'* from being raised too high.

Into the diverging side rails, *b b*, are mortised a front cross-rail, *e*, a rear cross-rail, *f*, and intermediate intersecting diagonal rails, *g g*. All of these rails *b b*, *e*, *f*, and *g g* are provided with harrow-teeth *h*, the shanks of which pass up through the several rails, and are secured in place by nuts *h'*.

45 The blades of the teeth *h* are preferably triangular in cross-section and incline rearwardly, as shown; but no claim is made herein to the construction of the teeth.

i designates a wooden axle, which is provided at each end with metal journals *k*, which are secured to it by clips *l l*.

m m designate the supporting-wheels for

riding the harrow, when necessary, and *n* designates the driver's seat, secured to the axle by springs *o o*, attached thereto.

55

About three feet from the rear ends of the side rails, *b b*, vertical iron axle-guides *p p*, about two and a half feet high, are secured. These axle-guides *p p* are rectangular at their tops, and have parallel arms *p' p'*, provided with shoulders *p' p'* near their lower ends. Their lower ends terminate in bolts *q q*, which pass down through the side rails, *b b*, one on each side of the axle *i*, and are secured in place by nuts on the under side of the rails *b b*.

60

To prevent lateral movement of the harrow-frame upon the axle *i*, stop-plates *r r r r* are secured to the axle *i* by bolts *s*, passed through the axle laterally. Two stop-plates *r r* are secured on each edge of the axle—one on each side of the axle-guide. The stop-plates for each axle-guide are similarly arranged. The weight end *t* of a lever, *u*, is connected by a short chain, *u'*, to the harrow-frame by an eyebolt passed through the diagonal rails at 70 their intersection. This lever *u* is fulcrumed in bearings *v* at the middle of the axle *i*, and extends back beyond the rear cross-rail, *f*, and is provided with a suitable handle.

At the middle of the rear rail, *f*, a hook, *w*, 80 is provided to engage the lever *u*, and hold the harrow up out of a working position when moving from field to field, or when it is desired to turn the harrow and back up into a corner to harrow ground that the ordinary 85 harrow cannot reach. The axle-guides give the harrow the necessary vertical play, and the stop-plates prevent unnecessary lateral play, while the weight of the driver in no way affects the harrow. The harrow covers the 90 wheel-tracks immediately, leaving everything smooth. It does not require to be loaded into a wagon or turned upon its side to move it from field to field, and there is no danger attending its transportation from place to place.

95

While the wheels do not lift the harrow while working, they keep it from slipping to the right or to the left, as other harrows do, even when they encounter a clod of small size.

Having thus fully described my invention, 100 what I claim as new, and desire to secure by Letters Patent, is—

In a sulky-harrow, the combination, with the frame *a*, constructed as described, of the axle

i, axle-guides *p p*, having the parallel vertical arms *p'*, provided with bolt ends *q* and shoulders *p²*, whereby they are connected to the side rails of the harrow-frame, as shown, to form durably-braced guides for the frame, the triangular stop-plates *r*, arranged at each side of the guide-arms *p'*, and secured to the axle by means of the bolts *s*, whereby lateral mo-

tion of the frame is prevented, substantially as specified.

In testimony whereof I affix my signature in presence of two witnesses.

FRANK L. RUMBLE.
